REGENERATOR WITH EXPANSIBLE AND CONTRACTIBLE MATRIX

Charles H. McCreary, Oak Park, Ill., assignor to General Motors Corporation, Detroit, Mich., a corporation of Delaware

Filed Oct. 27, 1966, Ser. No. 589,921
13 Claims. (Cl. 165—6)

My invention is directed to regenerators, which are devices in which a porous structure such as a disk, drum, or band is moved through two spaces divided from each other by a bulkhead and in which two different fluids flow through the matrix at each side of the bulkhead so that one fluid gives off heat to the matrix and the other absorbs heat from the matrix. Devices of this sort have been employed as furnace air pre-heaters and as regenerators in gas turbine engines, in each case transferring heat from hot exhaust gases to air prior to its entry to the combustion apparatus. However, regenerators are usable for various heat transfer purposes.

One problem with regenerators of this sort lies in the fact that gases are carried from one space to the other within the porous matrix. Thus, in a furnace some of the incoming air would be diverted to the stack and some flue gases would be mixed with the incoming air. The carry-through of gas becomes a more serious problem as pressure increases. In a gas turbine, for example, appreciable quantities of compressed air are carried by the matrix into the turbine exhaust and energy is thus wasted.

The basic point of my invention lies in the use of a matrix of an expandable and contractible nature; for example, a material having honeycomb-like cells which may be flattened or opened out. The matrix is at least partially collapsed at the point where it passes through the bulkhead from one space to the other, thus purging it of much of the gas which otherwise would be carried through in the cells of the matrix.

Another highly significant point of my invention lies in the fact that the matrix is flexible rather than rigid and thus may move in a suitable way or track of almost any configuration, with a varying degree of curvature, and with straight runs if desired.

A further significant but optional aspect of my invention lies in means for limiting the expansion and contraction of the matrix and for transmitting drive tension so that the driving load is carried independently of the cellular structure of the matrix.

The principal objects of my invention are to improve the efficiency of regenerators, to minimize carry-through of gas in such devices, and to provide a flexible matrix adapted to travel in paths of varying curvature.

The nature and advantages of the invention will be clear from the succeeding detailed description of preferred embodiments of the invention and the accompanying drawings.

FIGURE 1 is an axonometric view of a regenerator with parts cut away.

FIGURE 2 is a partial sectional view taken on the plane indicated by line 2—2 of FIGURE 1.

FIGURE 3 is a view similar to FIGURE 2 showing a modified structure.

FIGURE 4 is a sectional view taken on the plane indicated by line 4—4 of FIGURE 3.

The particular embodiment of the invention described herein is intended as an after-cooler for a compressor, but devices of the same character may be used for other purposes.

The regenerator comprises a housing 6 within which is mounted a matrix 7. Housing 6 defines an inlet 9 and

2

outlet 10 for one medium which flows in a generally straight line through the matrix. The upper and lower parts of the housing define spaces 11 and 12 for the second medium. The matrix moves in a path which comprises two straight runs joined by two semi-circular runs at each end, or what might be called a race-track path, being guided in shallow channel tracks 16 and 17 at the ends of the matrix which are supported on the housing. The matrix itself, as is apparent from the drawings, is a continuous band or belt and, as shown most clearly in FIGURE 4, is of a honeycomb-type structure defining cells or passages 18 extending through the matrix from the inner to the outer side. The matrix is made of flexible material such as very thin shim stock which is formed into a corrugated pattern. Each leaf 19 of the matrix is formed with corrugations extending from the inner to the outer side of the matrix, and the corrugations on the adjacent leaves are relatively reversed so that, when the leaves are placed together an expandable and contractible honeycombed structure somewhat analogous to that of paper Christmas tree ornaments results. With this sort of structure, if the web or band is put in tension the leaves flex and the cells or passages 18 are opened. Longitudinal forces compressing the matrix tend to close the cells.

In the preferred embodiment of the invention, the matrix is slowly moved through seals where it passes from one medium to the other and is propelled by rollers immediately ahead of the seals. The friction of the seals causes the matrix cells to collapse as they enter the seal and the traction of the next set of driving rollers opens the cells as they pass through the run from one seal to the next.

Referring now to FIGURES 1 and 2, the stationary structure of the regenerator includes an upper bulkhead or diaphragm 19 and a corresponding lower diaphragm 20 which provide a passage interconnecting the inlet 9 and outlet 10 and passing through both the straight runs of the matrix. The second medium flows radially through both the semicylindrical end portions of the matrix. This medium may enter inlets (not illustrated) at the top and bottom of the housing 6 and be discharged through an outlet 22 above the bulkhead 19 in the side wall of the housing and a corresponding outlet below the lower bulkhead. The matrix in this embodiment passes twice through each bulkhead and at each opening where it passes a bulkhead there is provided a seal 24 comprising seal bars 25 and 26 engaging the outer and inner faces of the matrix under the bias provided by springs 27 and 28. The tracks 16 and 17 are in close proximity to the outer ends of the matrix and, if desired, special sealing surfaces may be provided at these points.

The matrix is moved slowly along the supporting tracks by pairs of rollers 32 disposed immediately ahead of each seal 24. These are supported on the housing and they have shafts extending from the housing to be driven by any suitable means. As illustrated in FIGURE 1, the shafts 33 of the rollers of each pair bear pulleys which are interconnected by crossed belts 34. Belts 35 connect the pairs of driving rollers and one of the shafts has a connection (not illustrated) to suitable means for driving all the rollers slowly. All the belts are preferably of a positive drive type. Means such as spring 37 bias the rollers together and thus into contact with the matrix. The mode of operation of the device illustrated in FIGURES 1 and 2 should be clear from the foregoing, but may be described briefly. One medium, such as cooling air, is passed through the matrix from inlet 9 to outlet 10 and the other medium, such as compressor discharge air, flows radially through the end loops of the matrix. The rollers 32 are driven concurrently and slowly propel the

matrix in its circuit of the guiding tracks by frictional engagement with the matrix. The matrix passes through the bulkhead seals 24 immediately beyond each set of driving rollers and the pushing force of the rollers closes the cells of the matrix as illustrated at 39 in FIGURES 2 and 4, where it passes through the seal. The traction of the next set of drive rollers expands the matrix in the succeeding path until it reaches the rollers where it is again collapsed where it passes through the cells. Thus, the two fluids can flow readily through the expanded matrix and are squeezed out of the matrix to a very large extent before it passes through the seals.

FIGURES 3 and 4 illustrate features not shown in FIGURES 1 and 2. The matrix is a chain of segments, each segment consisting of a number of leaves 19 disposed between two rigid end sheets 40. The sheets 40 provide partitions between the adjacent segments. Also, a lost motion push-pull connection is provided between adjacent partitions which limits the amount of expansion and contraction of the cellular material of the matrix. The partitions 40 have bumpers 42 extending from them at each face and edge of the matrix, as shown at the top of FIGURE 4 and in FIGURE 3. The bumpers 42 are in engagement where the matrix passes through the seal, and also the bumpers 42 at the radially inner side of the matrix are in engagement as it passes around the curved portions of the track. The bumpers thus provide a means other than the matrix leaves to limit the degree of contraction of the matrix, and also to transmit the pushing force where the matrix goes through the seal. There is also a lost-motion tension connection provided by bent wire pieces 44 which extend through holes in the partition at each edge of the matrix. The rods 44 have bent-over ends 45 which define heads to limit their movement from the partition and each rod 44 includes a loop 46 which encircles a companion rod 44. In the lower part of FIGURE 3, the tension connection is fully extended with the heads 45 against the partitions 40, and the connection slips together at the seal and around the end curve. Note that the ends of the bumpers are rounded off as shown in FIGURE 3. The operation of the regenerator with the matrix of FIGURES 3 and 4 is the same as previously described.

The description of the preferred embodiments of the invention to explain the principle thereof is not to be considered to limit the invention, since many modifications may be made by the exercise of skill in the art.

I claim:

1. A regenerator comprising, in combination: a continuous matrix of expansible and contractible porous structure a bulkhead having at least one opening for passage of the matrix means for moving the matrix progressively through the opening and means for compressing the matrix in the direction of movement thereof to contract the matrix at least partially at the opening so as to minimize carry-through of fluid by the matrix.
2. A regenerator as recited in claim 1 in which the

means for compressing the matrix includes a seal in frictional contact with the matrix at the opening.

3. A regenerator as recited in claim 1 in which the means for moving the matrix through the opening is a pair of friction drive rollers engaging opposite faces of the matrix.

4. A regenerator as recited in claim 1 in which the matrix comprises a series of segments

each segment having a plural number of flexible corrugated sheets defining passages between the sheets.

5. A regenerator as recited in claim 4 including also rigid partitions disposed between the segments.

6. A regenerator as recited in claim 5 including also lost-motion push-pull connections between the partitions limiting the range of separation of adjacent partitions.

7. A regenerator comprising, in combination:

a housing bulkhead means dividing the interior of the housing into at least two spaces

an endless matrix forming a loop

means guiding the matrix for movement through the spaces and through openings in the bulkhead means

a seal in frictional contact with the matrix at a said bulkhead opening, and

means adjacent to and ahead of the seal engaging to the matrix for driving the matrix

the matrix having a structure defining passages through the matrix expansible and contractible in the direction of movement of the matrix adapted to be contracted by friction in the seals and expanded between the seals.

8. A regenerator as recited in claim 7 in which the matrix is of a cellular or honeycomb type of structure.

9. A regenerator as recited in claim 8 in which the matrix comprises thin flexible corrugated sheets bonded together to define a cellular structure expansible and contractible by flexure of the corrugations.

10. A regenerator as recited in claim 7 in which the matrix comprises a chain of expansible segments and rigid partitions disposed between the segments.

11. A regenerator as recited in claim 10 including also lost-motion tension connections between the partitions.

12. A regenerator as recited in claim 11 including also bumpers defining a minimum space between the partitions.

13. A regenerator as recited in claim 10 including also bumpers defining a minimum space between the partitions.
